BRASSIÈRE

Karl Van Leuven, Jr., Hollywood, Calif., assignor
to Ina Yoakum, Los Angeles, Calif.

Application December 23, 1946, Serial No. 717,941

5 Claims. (Cl. 2—42)

1

This invention relates to breast supports and deals more particularly with a brassière.

A general object of the invention is to provide a brassière more particularly adapted for use with low cut dresses, play suits or swim suits, providing proper support for only the under portion of the breasts whereby unnatural binding is obviated and the upper chest, including the upper breast portions, remains resilient and soft.

Another object of the invention is to provide a brassière of the type indicated, which is adapted to be constructed as a separate garment or be embodied in and as part of play suits, swim suits and halter-type garments.

Another object of the invention is to provide a brassière having separate, similar, but oppositely formed breast-engaging cup portions, and interconnecting said cup portions by means of generally stiff yet bendable and resilient means whereby a desired separation of the breasts can be made by a suitable adjustment of the interconnecting means.

Another object of the invention is to provide a brassière, as indicated, having shoulder-supporting straps which are attached to the breast-engaging cups at the ends of the mentioned cup interconnecting means, whereby the pull of the straps is exerted on a generally rigid part to obviate distortion of the brassière, and whereby the straps pass over the shoulder along the normal seams between the dress and its sleeves, if any, to be hidden by said seams.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes embodiments of the present invention, which are given by way of illustration or example only.

In the drawings, like reference characters designate similar parts in the several views.

Fig. 1 is a front perspective view of a shoulder-supported brassière in use.

Fig. 2 is an enlarged broken front view, in flat condition, of the left-hand breast-supporting cup.

Fig. 3 is a further enlarged cross-sectional view as taken on the line 3—3 of Fig. 2.

Fig. 4 is a front perspective view of an alternate form of brassière for embodiment in a garment.

The brassière which is illustrated in Figs. 1 and 2 comprises, generally, a pair of identical but oppositely formed breast-supporting cups 10, a

2

back-engaging extension 11 integrally formed with each cup 10, a shoulder strap 12 for each cup, wire means 13 inter-connecting the cups at the middle of the body between the breasts, and a pre-formed stiffener insert 14 for each cup.

The construction of Fig. 4 is similar except for the omission of the extensions 11 inasmuch as the brassière shown is intended for incorporation in a garment, as stated.

With particular reference to Figs. 2 and 3, the cup is formed of an outer piece of fabric 15 to have a lower edge 16 designed to circumferentially follow the meeting line of the breast and the body. The upper edge 17 of said piece of fabric is shaped to extend along a generally horizontal medial line of the breast whereby the cup covers only the lower portion of the breast. The edges 16 and 17 meet at a point 18 corresponding to a point adjacent to the middle of the body. The fabric piece 15, opposite to the point 18, is extended laterally and somewhat downwardly to form the back-engaging extension 11.

The cup 10 further includes an inner fabric piece 19 which may be made of felted material and have the same shape as the fabric piece 15 except for the extension 11. The fabric pieces, except for the extension 11, are co-extensive and are secured along the edge portions as by a line of stitching 20 to form a pocket 21 for the stiffener 14.

The strap 12 conventionally comprises an adjustable ribbon secured at points 22 and 22a at the side edges of the cup 10 and adjacent the end of extension 11, respectively. As shown, the ribbon is extended as at 23 along the inner portion of the lower edge 16 of the cup to terminate at the point 18. Spaced lines of stitching 24 secure the ribbon part 23 in place and form an elongated pocket 25 between the cup fabric parts 15 and 19 for the wire means 13.

The wire means 13 comprises a single length of preferably enamel covered wire which is inherently stiff and yet capable of being bent and having limited resiliency or springiness. The wire means is formed to have curved end portions 26 residing in the pocket 25 of each cup and each terminating adjacent the point 22 of each respective cup 10. Each end portion 26 is reversely bent at 27 near the point 18 of each cup and then formed in a curved loop 28 which passes out of the pocket 25 through an opening 29 provided in the fabric piece 15. The two loops 28 have their ends 30 directed downwardly and toward each other to be integrally joined as at 31.

By means of the above-outlined construction, the breasts are supported from beneath, the wire ends 26 provide a rigid yet formable means for defining the shape of the breasts, the loops 28 afford resiliency, providing for variable alignment of the breast-supporting cups, and the

straps have their pull applied at the outer sides of the cups and at the ends of the wire so that they pass around rather than over the breasts and are thereby widely spaced for low neckline garments.

The inserts 14 are provided for molding the breasts so they have spherical form. Said inserts reside in pockets 21 and are preferably formed of laminated gauze impregnated with cellulose dissolved in acetone. Being thermoplastic, said inserts are adapted to be pre-formed to be curved both longitudinally and transversely and are, therefore, quite stiff yet reasonably pliable. The lower edge 32 of each insert generally follows the curvature of edge 16. The opposite edge 33, however, is concavely curved to leave each cup 10 with a quite soft and pliable crescent shaped part 34 at the upper part thereof.

It will be noted that the curved loops 28 are disposed to have overlapping relation to the adjacent parts of the cups 10, and it will be evident that said loops bear against the outer surfaces of said cups to separate them. As seen best in Fig. 2 the inserts 14 receive this resilient pressure, and, because of their stiffness, are urged bodily laterally to thereby effect desired separation of the breasts. In this manner the wire means 13 and the inserts 14 cooperate to resiliently support the breasts in any desired degree of separation.

The brassière shown in Fig. 4 is substantially similar to the form above described, except that the extensions 11 and straps 12 are omitted and instead of the described connecting part for the wire ends 26, said connecting part is formed as a simple straight connection 35. The outer ends of the wire ends 26 are formed as hooks 36 engaged in eyelets 37 and the wire is thereby held against endwise displacement. By slipping said hooks 36 through the eyelets, the wire can be removed for laundering of the cups. By sewing this brassière into a garment, the mentioned advantages are obtained.

Only the essentials of the brassière have been disclosed. Conventional tapes and stitching may be employed where desired to finish off the garment. Also, suitable lines of stitching may be passed through the outer and inner fabric pieces and the stiffener 14 to unify the construction.

While I have illustrated and described what I now regard as the preferred embodiments of my invention, the construction is, of course, subject to modifications without departing from the spirit and scope of my invention. I, therefore, do not wish to restrict myself to the particular forms of construction illustrated and described, but desire to avail myself of all modifications that may fall within the scope of the appended claims.

Having thus described my invention, what I claim and desire to secure by Letters Patent is:

1. A brassière comprising a pair of separately formed breast-supporting and stiffened cups each having an elongated pocket extending along the lower edge thereof, and an integral length of wire connecting the cups and comprising ends arranged in said pockets and a re-entrantly bent portion connecting said wire ends and formed with laterally and oppositely directed loops, said loops having overlapping engagement with the forward outer side of the cups to bear against and yieldingly separate the same.

2. A brassière comprising a pair of separate breast-supporting and stiffened cups each having an elongated pocket extending along the lower edge thereof, the pocket of each cup, at the end

adjacent to the other cup, having a forwardly directed opening, and wire means connecting the cups, said wire means comprising curved lengths thereof residing in the mentioned pockets and extending substantially throughout the length of each said pocket, said wire lengths having ends that are adjacent, an integral reversely bent portion on each said adjacent end and extending outwardly through the forwardly directed opening of each respective pocket in said cups, and a looped and integral portion connecting the outwardly extending ends of the reversely bent portions and comprising laterally and oppositely directed resilient parts in overlapping engagement with the forward outer faces of the adjacent ends of the cups to yieldingly spread said cups apart.

3. A brassière comprising a pair of separate breast-supporting and stiffened cups each formed to engage only the under portions of the breasts, and means to connect the cups comprising an integral length of wire having a portion extending between and connecting the cups and having end portions generally following and reinforcing the bottom edges of the cups and terminating at opposite sides of the brassière, the adjacent ends of the cups being each provided with a forwardly directed opening, the mentioned cup-connecting wire portion extending from the adjacent ends of the end portions of the wire through said forwardly directed openings to the forward outer side of the cups, said cup-connecting wire portion being provided with laterally and oppositely directed parts in overlapping engagement with the forward outer faces of the adjacent ends of the cups to bear against and spread the cups apart.

4. A brassière according to claim 3 in which the cups are each stiffened by a pre-formed doubly curved stiffener insert arranged to mold the portions of the breasts supported by the cups, said inserts having portions residing in the portions of the cups that are adjacent and beneath the outer faces thereof, whereby the laterally and oppositely directed parts of the cup-connecting wire portion bear on said inserts through said cup faces.

5. A brassière according to claim 3 in which the cups are each stiffened by a pre-formed doubly curved stiffener insert arranged to mold the portions of the breasts supported by the cups, said inserts having portions residing in the portions of the cups that are adjacent and beneath the outer faces thereof, whereby the laterally and oppositely directed parts of the cup-connecting wire portion bear on said inserts through said cup faces, and a shoulder strap connected to each cup at the terminations of the end portions of the cup-connecting means at the opposite ends of the brassière, whereby said brassière is supported only at said opposite ends and the breasts are resiliently supported by the cup-connecting portion that extends between the cups.
